Atty.

UNITED STATES PATENT OFFICE

95,698

DESIGN FOR AN ADJUSTABLE MIRROR FRAME AND SUPPORT THEREFOR

Vincent D. Milliken, St. Joseph, Mich.

Application September 27, 1934, Serial No. 53,409

Term of patent 7 years

To all whom it may concern:

Be it known that I, Vincent D. Milliken, a citizen of the United States, residing at St. Joseph, in the county of Berrien and State of Michigan, have invented a new, original, and ornamental Design for an Adjustable Mirror Frame and Support Therefor, of which the following is a specification, reference being had to the accompanying drawing, forming a part thereof, in which:

The figure is a perspective view of an adjustable mirror frame and support therefor, showing my design.

I claim:

The ornamental design for an adjustable mirror frame and support therefor, substantially as shown.

VINCENT D. MILLIKEN.
